(57) **CLAIM**

The ornamental design for a shoelace ornament, as shown and described.

DESCRIPTION

FIG. 1 is a perspective view of a shoelace ornament, showing my new design, shown in a used condition attached to a star and shoelace shown in broken lines; FIG. 2 is a rear elevational view thereof, shown in an unused condition;

FIG. 3 is a front elevational view thereof;

FIG. 4 is a left side elevational view thereof, the right side elevational view being a mirror image thereof; and, FIG. 5 is a top plan view thereof, the bottom plan view being a mirror image thereof.

The broken lines showing a shoelace and star in FIGS. 1 and 6 depict environmental matter and form no part of the claimed design. The dashed-dot lines adjacent to the shaded area represent the boundary lines of the claimed design.
